BOOK

Leon Ottinger, New York, N. Y.

Application March 7, 1935, Serial No. 9,724

6 Claims. (Cl. 281—42)

This invention relates to improvements in the mechanical construction of books, magazines, pamphlets and the like, and, more especially, to the provision of a place-marker or bookmark which forms a part of the book.

It not infrequently happens when using the ordinary place-marker that it becomes separated from the book, or transferred to some other book, so that when the reader, at a later time, wishes to turn quickly to the desired page, he is unable to do so. One of the objects of the present invention is, accordingly, to provide a place-marker which cannot become separated from the book in which it is used, and which, moreover, can be provided without materially increasing the cost of the book.

Bookmarks have heretofore been proposed which form a part of a book cover of the type used for the protection of books against being soiled by the hands of the reader. These bookmarks, however, were formed as a projection extending from the edge of one or both of the leaves or sheets constituting the book cover. Book or place-markers constructed in this way, however, have the disadvantage of substantially increasing the cost of the article. Such marker portions projecting from the edges of the book cover were made in two ways: (1) by forming them integrally with the edge of the leaf; (2) by making the marker separately and attaching it to the edge of the leaf by the use of paste, for example. Either method of manufacture, however, is comparatively expensive, the first because of the necessity of complicated punches and dies, and because of wastage of stock in punching, and the second because of the labor required in attaching the marker.

In accordance with my present invention, however, the difficulties with such constructions are overcome, and a book or place-marker is provided at an insignificant increase in the cost of the book to which it is applied. The marker may be formed as a part of one of the cover leaves, fly leaves or interior leaves of the book or as a part of the jacket (usually of paper), such as is commonly furnished to protect, more or less temporarily, the cover leaves of books, or it may be formed as a part of those book covers which are manufactured separately from the book itself and applied thereto to serve as a more or less permanent protection for the book.

Another object of my invention is to provide a place-marker which is peculiar to the book with which it is used. It is frequently desirable to bring into prominence the author or the pub-

lisher of a book or to emphasize some characteristic of the book such, for example, as a peculiarity of a character in the book or the general subject matter to which the book relates. This may be accomplished not only by means of matter appearing on the bookmark but by giving the bookmark a configuration appropriate to the matter desired to be emphasized.

A further consideration in the manufacture of books, magazines, pamphlets and the like, and, perhaps, particularly important in connection with magazines and periodicals, is the advertising value of the cover leaf space and the space on the leaves adjacent the cover leaves, and the present invention also aims to provide a place-marker which is so associated with one or more of the leaves of the book, particularly the outside cover sheets or leaves and the pages adjacent thereto, as to enhance the advertising value of the space on such pages.

The nature of the invention is set forth in the following description and accompanying drawing which shows several forms in which the invention can be embodied, but it is to be understood that the disclosure is illustrative only, and that the details of construction may be changed without departing from the principles of the invention or exceeding the scope and meaning of the terms of the appended claims.

In the drawing—

Fig. 1 is a plan view representing the outside cover of a book with the bookmark or place-marker of my invention in the position occupied by the marker before manipulating the device into position between the leaves of the book;

Fig. 2 is a similar view with the bookmarking device folded upwardly ready to be inserted between the leaves of the book;

Fig. 3 shows a cross section of the book with the bookmark folded over the top edge of a portion of the book and with the outer end and body of the marker inserted between the leaves to which it is desired to reopen the book at a later time.

Fig. 4 is a view of a modification in which the marker is given the configuration of an object desired to be emphasized, a bottle in this case, and as shown, the marker will fold over the bottom edge of the book instead of the top edge as shown in Figs. 1, 2, and 3; and

Fig. 5 is a plan view similar to Fig. 1 except that the marker is disposed along the width of the cover instead of the length of the cover as in the previous figures.

Fig. 6 is a perspective view of the book shown

in Fig. 5 with the bookmarker folded over the side edge of a portion of the book and with the outer end of the marker in position so that when the book is closed, the marker will be located between the leaves to which it is desired to reopen the book at a later time.

Referring more particularly to Figs. 1 to 3, the cover 10 of a book, magazine or the like is cut, perforated or scored along the lines 11, 10 to provide a flap 12 which may be lifted from the body of the leaf and used as a marker. Where the cover or leaf is scored or perforated, it is necessary to sever the flap along the lines of the scoring or perforation. As shown in Fig. 15 1, the flap 12 has been partially severed from the cover 10 along one end and the two sides of the flap 12 leaving one end of the flap 12 attached to the cover.

To use the flap as a bookmarker, the flap 12 20 is folded upwardly as shown in Fig. 2 and then folded over the top edge of a portion of the book and the free end of the flap 12 is inserted as shown in Fig. 3, between the leaves to which it is desired to reopen the book at a later time. It 25 will be observed that when the flap 12 is raised from the body of the cover 10 a window 14 is provided in the cover 10 through which matter on the adjoining page is exposed. This feature may be used in a variety of ways, e. g., for advertising 30 purposes. Likewise the flap 12 may bear suitable advertising matter.

In Fig. 4 the flap 12 is given a distinctive outline, in this case the shape of a bottle, and the outline is formed by scoring or perforations 11. 35 The bottle or flap is severed from the body of the page or cover 10 along the lines of scoring or perforations 11, the scoring or perforations 11 being absent along a certain length of the outline of the flap 12 so that it shall at some point 40 remain attached to the body of the page or cover 10. In this figure the flap is shown so disposed that when severed along the scoring or perforations 11 it can be folded over the bottom edge of the book or magazine instead of over the top edge 45 as in Figs. 1, 2, and 3.

In Fig. 5 the flap 12 is shown outlined on the cover 10 by perforations 11. In this instance the flap is shown disposed along the width of the page instead of the length of the page as in the 50 previous figures. When the flap has been severed from the cover or page along the lines of perforation shown, it may be used as a bookmarker by folding the flap around the side edge of a portion of the book and the free end of the flap inserted 55 between the pages to which it is desired to reopen the book at a later time. This is shown in perspective in Fig. 6.

The bookmarker of the present invention may be provided at practically no increased cost in 60 the manufacture of the book inasmuch as the scoring, perforating or cutting operation may be performed at the same time as the printing operation merely by providing the printing plate for the bookmarker page with suitable means 65 to cut, score or perforate the flap.

The invention has been particularly described in connection with the outside cover or jacket of a book or magazine but the marker may also be formed as a part of one of the fly leaves or 70 interior leaves of the book and may be applied to all kinds of books in which a bookmarker is desirable, such as notebooks, diaries and the like,

as well as to magazines, pamphlets, newspapers and the like.

In the accompanying claims the word "book", in addition to its ordinary meaning, is intended to include magazines, booklets, pamphlets, circulars, newspapers and the like and the word "leaf" is used to comprehend any pages of a book including the fly leaf and cover as well as part of a jacket or other protective covering for a book.

I claim:

1. A book having a leaf thereof provided with a portion separable in part from the body thereof, said portion being adapted to be folded along the non-separable part of said portion from the plane of the leaf and around one of the edges of the leaf to form a flap or tab which is insertable between the leaves of the book to serve as a place marker.

2. A book having a leaf thereof provided with an elongated portion severable at its edges from the leaf but attached at one end to said leaf and foldable at that end from the plane of the leaf and around one of the edges thereof to form a flap or tab which is insertable between the leaves 25 of the book to serve as a place marker.

3. A book having a leaf thereof provided with a portion severable along three sides from the leaf and adapted to be folded along its fourth side out of the plane of the leaf and around an edge thereof to form a flap or tab insertable between the leaves of the book to serve as a place marker.

4. A book having a leaf thereof provided with a central portion separable in part from the body 35 thereof, said portion being adapted to be folded along the non-separable part of said portion from the plane of the leaf and around one of the edges of the leaf to form a flap or tab which is insertable between the leaves of the book to serve as a 40 place marker, and, when so used, creating a window through which matter on adjoining pages is exposed.

5. A book having a leaf thereof provided with a marking portion which at one side is integral with 45 the main portion of the leaf and which at its other sides is removable readily from the plane of the leaf, the length of said marking portion from the side at which it is attached to the main portion of the leaf being greater than the distance 50 between the line of attachment to the main portion of the leaf and the edge of the book in the direction opposite to that in which the marking portion extends, plus the thickness of the book, whereby said portion may be bent around said 55 edge of the book and inserted between any of the leaves thereof.

6. A book having a leaf thereof provided with an elongated marking portion, which at one side is integral with the main portion of the leaf and 60 which at its other sides is separated from the main portion of the leaf, the length of said marking portion, from the side at which it is attached to the main portion of the leaf being greater than the distance between the line of attachment to 65 the main portion of the leaf and the edge of the book in the direction opposite to that in which the marking portion extends, plus the thickness of the book, whereby said portion may be bent around said edge of the book and inserted between any of the leaves thereof.

LEON OTTINGER.
